Primary Examiner—Susan J. Lucas

[21] Appl. No.: 3,614

CLAIM

[22] Filed: Jan. 11, 1993

The ornamental design for a decorative light enclosure,
as shown and described.

[52] U.S. Cl. D26/125; D11/121;
D21/168; D26/94

DESCRIPTION

[58] Field of Search 362/806, 808, 124;
428/3, 7, 11; D9/311, 312, 316; D26/4, 73, 94,
99, 100, 125, 126; D11/117, 121, 160; D21/155,
168

FIG. 1 is a perspective view of a decorative light enclosure
showing my new design;

FIG. 2 is a front elevational view thereof;

FIG. 3 is a bottom view thereof;

FIG. 4 is a top view thereof;

FIG. 5 is a right side view thereof;

FIG. 6 is a left side view thereof; and,

FIG. 7 is an environmental front elevational view
thereof, with a portion broken away to reveal the interior
of the design.

The broken line showing of a light fixture in FIG. 7 is
for illustrative purposes only and forms no part of the
claimed design.
